UNITED STATES PATENT OFFICE.

HARVEY H. DICK, OF LINCOLN, ILLINOIS.

BOILER-CLEANER.

1,392,307.

Specification of Letters Patent.

Patented Oct. 4, 1921.

Application filed October 31, 1917. Serial No. 199,414.

To all whom it may concern:

Be it known that I, HARVEY H. DICK, a citizen of the United States, residing at Lincoln, in the county of Logan and State 5 of Illinois, have invented a certain new and useful Improvement in Boiler-Cleaners, of which the following is a full, clear, concise, and exact description, reference being had to the accompanying drawings, forming a 10 part of this specification.

My invention relates to devices for cleaning boilers.

The principal object of the invention is to provide a practical and efficient device for 15 cleaning boilers and the like.

Another object of the invention is to arrange for the skimming or removal of the scum and other refuse matter at or near the surface of the water, and also to remove the 20 sediment settling in the water below the surface, by one and the same device.

Another object of the invention is to provide a device which shall be simple and inexpensive to construct and highly efficient 25 and satisfactory in operation.

In the accompanying drawings Figure 1 is a vertical longitudinal section of a boiler provided with a cleaning device embodying my invention;

30 Fig. 2 is a plan view on an enlarged scale of a portion of the cleaning device shown in Fig. 1, said Fig. 2 being taken on line 2—2 in Fig. 1;

Fig. 3 is a vertical section of a part of the 35 device taken on line 3—3 in Fig. 4; and

Fig. 4 is a section taken on line 4—4 in Fig. 3, showing the boiler also.

Referring to the drawings, I show in Fig. 1 a boiler 1 which is an ordinary type of 40 boiler well known on the market, although of course the device can be applied to boilers of various makes. The cleaning device embodying my invention is shown at 2 and is preferably located about the central portion of the boiler. This cleaning device is in 45

the form of a tank or vat, preferably of substantially V-shaped cross section, and of much greater length than breadth. It is suspended from the top of the boiler by 50 means of links 3, turnbuckles 4 and bolts 5 passing through the wall of the boiler. This tank or receptacle 2 is preferably made of two end portions or parts 2^a, and 2^b, and a central portion 2^c. It is formed by a series 55 of V-shaped transverse frames 6, 7, 8 and 9, arranged at intervals and serving as sup-

ports, the ribs 6 and 9 being at the ends and 7 and 8 between the ends, forming the ends of the middle portion 2^c. Sheet metal sides 10 and 11 are secured to the outer edges of 60 these frames 6, 7, 8 and 9. Sheet metal ends 12 and 13 are secured to the endmost frames 6 and 9. The portions of the sides 10 and 11 between the frames 6 and 7, and 8 and 9, respectively, are provided with apertures or 65 openings which may be conveniently formed by punching out portions of the sheet metal forming said sides, such punched out portions being shown at 14 and 15. The ends 12 and 13 are also provided with apertures or 70 openings conveniently formed by punched out portions 16 and 17. The portions of the sides 10 and 11 between the frames 7 and 8, are preferably not provided with side apertures but with solid or closed, as shown in 75 Figs. 1 and 2. Thus the tank or vat-like structure is provided with a series of horizontally extending side and end openings, which are arranged at different horizontal levels. The punched out portions 14, 15, 16 80 and 17 form projections which extend to the side and end intake openings and which are inclined toward the same so that the movement of the water in the boiler and the slight washing around of the same due to 85 variations in water level, will cause scum and refuse matter to be caught on said projecting members and to be washed into the interior of the tank.

A pipe 20 is extended along the bottom of 90 the device, in effect forming the bottom of the same, said pipe being substantially the length of said tank or vat. This pipe 20 is preferably provided with a series of openings establishing communication between the 95 interior of the pipe and the interior of the tank 2, as for example, the longitudinally extending openings 21—21 in the top surface of said pipe. Sediment from the water may enter these slots 21 and pass into the pipe 20 100 to be discharged therefrom as hereinafter explained.

An outlet or discharge device preferably in the form of a funnel shaped member 23 is arranged within the tank-like member 2, 105 to receive scum and other refuse matter which may be on or near the surface of the water. Preferably the member 23 has a closed top 24 and is provided with side openings 25 affording communication with the 110 interior. Said member 23 is mounted on the pipe 26 which extends down to and is se-

cured to the pipe 20. Thus the scum or other refuse which comes from the surface of the water and enters the member 23 will pass down the pipe 26 and into the pipe 20 and 5 be carried off with the sediment which enters said pipe 20 through the slots 21.

A discharge pipe 27 extends upwardly from the intake pipe 20, preferably near the middle of the same, and is secured to the 10 top of the boiler 1 by means of a coupling 28. A discharge valve 29 in said pipe 27 controls the discharge of matter from the pipe 20.

An inlet pipe 30 preferably extends down 15 into the boiler through the top thereof and is desirably provided at its lower end with an upturned member 31 so that water entering through the pipe 30 will not be directed downwardly, but instead will be directed 20 upwardly and therefore will not stir up the sediment at the bottom of the cleaning device. An intake 32 is also preferably provided, the same having inlet apertures 33 in its lower surface and being connected 25 with the pipe 20 by a small pipe 34. By having the apertures 33 in the under side of the member 32, no sediment will drop into said apertures 33.

From the foregoing it will be seen that 30 the water in the boiler will enter the device through its side and end openings, being always able to enter same even though the height of water in the boiler may vary, because of said openings being at different 35 heights. The scum and other refuse matter resting on or near the surface of the water will accumulate within the device 2 because the water will be comparatively quiet from the boiling, and the sediment 40 will also collect there to a large extent. The scum and other light refuse matters will enter the apertures in the funnel-shaped member 23 and be carried into the pipe 20. The sediment will descend and 45 enter apertures 21 in pipe 20. When the discharge valve 29 is opened all these matters will be discharged through the outlet pipe 27, thereby ridding the boiler of these 50 objectionable elements which have very disastrous results in boilers as is well known.

By the turnbuckle arrangement including

the parts 3, 4 and 5, the device may be disconnected and moved to one side or the other with ease. This will permit complete removal of the cleaner or partial removal 55 of the same for convenience of access and examination.

The device is exceedingly simple and therefore inexpensive. Moving parts, floats and other objectionable features are avoided. 60

It will be understood that changes and modifications may be made without departing from the spirit of the invention.

What I claim is:

1. A device of the class specified comprising a tank or receptacle constructed of a plurality of substantially V-shaped frames and side and end walls secured to the outer edges of said frames, said end walls and end portions of said side walls 70 being provided with intake orifices at different levels, and a discharge pipe at the angle forming the bottom of said tank or receptacle, said discharge pipe being provided with intake orifices, and a funnel 75 shaped intake member mounted on a pipe supported by said intake pipe, said funnel shaped member having a closed top and side intake orifices.

2. A device of the class specified comprising a V-shaped tank having a central portion separated by transverse walls from the end portions, said transverse walls and also the outer walls of said end portions being provided with intake orifices arranged at 85 different horizontal levels, a pipe extending along the angle at the bottom of said tank or vat and provided with intake orifices, intake members located one in each of said end portions, said members consisting 90 of funnel shaped bodies mounted on pipe sections which extend down to said pipe, said funnel shaped members being provided with annular intake members with side orifices and a discharge pipe connected with 95 said first mentioned pipe and extending upwardly from the same in the central portion of the tank.

In witness whereof, I hereunto subscribe my name this 23rd day of October, A. D. 100 1917.

HARVEY H. DICK.
